UNITED STATES PATENT OFFICE.

FERDINAND KOHL AND WILLIAM SEVERNS, OF CHICAGO, ILLINOIS.

FOUNTAIN-MOP.

1,173,194.

Specification of Letters Patent. Patented Feb. 29, 1916.

Application filed November 27, 1914. Serial No. 874,242.

To all whom it may concern:

Be it known that we, FERDINAND KOHL and WILLIAM SEVERNS, citizens of the United States, residing at Chicago, in the county of Cook and State of Illinois, have invented certain new and useful Improvements in Fountain-Mops, of which the following is a specification.

The present invention relates to improvements in fountain mops, and has particular reference to such apparatus adapted for use in cleaning automobiles or the like, while not necessarily restricted to such use.

An important object of the invention is to provide a mop of the above mentioned character, so constructed that the fibrous mop-head may be readily and conveniently removed from and placed upon the supporting frame, when desired.

20 A further object of the invention is to provide apparatus of the above mentioned character, which is simple in construction, inexpensive to manufacture, convenient in use, strong and durable.

25 Other objects and advantages of the invention will be apparent during the course of the following description.

In the accompanying drawings forming a part of this specification and in which like numerals are employed to designate like parts throughout the same, Figure 1 is a plan view of a fountain mop embodying the invention, Fig. 2 is a central longitudinal sectional view through the same, and, Fig. 3

35 is a bottom plan view of the supporting frame, with the fibrous mop-head removed.

In the drawings, wherein for the purpose of illustration is shown a preferred embodiment of our invention, the numeral 5 designates a fibrous mop-head as a whole, embodying a fibrous tubular portion 6, having its lower side more or less open and carrying depending layer or layers of cord or strands 7, as shown. The tubular portion 6 is of course flexible and is removably mounted upon a tubular supporting frame 8. This tubular supporting frame embodies preferably longitudinally curved tubular arms 9, the forward ends of which are spaced a substantial distance apart, forming a permanent mop-passage or gap 10, which permits of the removing of the tubular portion 6 from the supporting frame and the replacing of the same thereon. The forward

spaced ends of the arms 9 are closed by 55 plugs 11, or other suitable means. The preferably curved arms 9 are provided upon their lower faces with preferably equi-distantly spaced outlet apertures 12, discharging the water downwardly into the strands 60 of the mop. The rear portions of the tubular arms 9 are preferably rigidly connected with a T-coupling 12', having a valve structure 13, connected therewith. This valve structure embodies a movable valve 14, 65 to control the supply of water to the tubular arms 9. Rigidly connected with the rear end of the valve structure 13 is a tubular handle-portion 15, for connection with a 70 hose or the like.

While we have shown the supporting frame 8 as preferably substantially circular, we do not wish to restrict the invention to this or any other particular shape, so long as a construction is preserved embodying a 75 supporting frame for removably holding the mop-head, and having a passage or gap preferably in its forward portion or forwardly of the connection of the rear portion thereof with the handle.

80 In the use of the apparatus, the valve 14 is opened, and the water passes into the perforated tubular arms 9. The water is discharged downwardly through the apertures 12, passing into and through the fibrous 85 mop head 5, which is moved in engagement with the automobile or other object to be washed or cleaned.

When the fibrous mop-head becomes too dirty or worn out, the same may be readily 90 removed from the supporting frame, by the operator catching hold of the tubular portion 6 at the opening 10, and drawing this portion forwardly, as indicated in dotted lines at 15', the ends of the tubular body 95 portion sliding forwardly upon the tubular arms 9, as shown at 16', until completely removed therefrom. It is obvious that a new mop-head may be readily replaced upon the supporting frame.

100 It is to be understood that the form of our invention herewith shown and described, is to be taken as a preferred example of the same and that various changes in the shape, size, and arrangement of parts may be resorted to without departing from the spirit of the invention or the scope of the subjoined claim.

Having thus described our invention, we claim:—

A mop of the character described, comprising longitudinally curved tubular arms having their forward ends closed and spaced and their opposite ends screw-threaded and provided with apertures between such ends, a T-coupling receiving the screw threaded ends of the tubular arms, a valve structure connected with the T-coupling, a tubular handle connected with the valve structure,

and a mop-head embodying a tubular body portion adapted to be removably mounted upon the curved arms.

In testimony whereof we affix our signatures in presence of two witnesses. 15

FERDINAND KOHL.
WILLIAM SEVERN.
